UNITED STATES PATENT OFFICE

169,051

CASING FOR A WEIGHING SCALE

Cyril Best, Deptford, London, England, assignor
to Molins Machine Company, Limited, London,
England, a company of Great Britain

Application September 5, 1952, Serial No. 21,354
In Great Britain April 7, 1952

Term of patent 14 years

(Cl. D52—10)

To all whom it may concern:

Be it known that I, Cyril Best, a citizen of Great Britain, residing at Deptford, London, S. E. 8, England, have invented a new, original and ornamental Design for a Casing for a Weighing Scale, of which the following is a specification, reference being had to the accompanying drawing, forming a part hereof.

Figure 1 is a front view of a casing for a weighing scale, showing my new design;

Figure 2 is a side view thereof; and
Figure 3 is a rear perspective view.

I claim:

The ornamental design for a casing for a weighing scale, as shown.

CYRIL BEST.
